HELICAL ANTENNA NULL SUPPRESSOR
Paul M. Pan, Adelphi, Md., assignor to General
Electric Company, a corporation of New York
Filed Feb. 17, 1959, Ser. No. 793,822
15 Claims. (Cl. 343—895)

This invention pertains to electromagnetic radiation systems and more particularly to means for controlling the pattern of radiation transmitted by electromagnetic radiation systems.

Generally, electromagnetic radiation systems include an antenna and a signal source for exciting the antenna. Currents flowing through the antenna while under excitation cause electromagnetic waves to be radiated by the antenna. The direction and intensity of propagation of the electromagnetic waves is the radiation pattern of the electromagnetic radiation system. In many applications, such as the transmission of television signals from a transmitter to numerous receivers surrounding the antenna, a pattern in an azimuth plane is desired.

Often it is not only sufficient to develop a radiation pattern in the azimuth plane, but the intensity of the radiation at particular azimuth angles must be controlled. For example, if it is known that a substantial portion of the receivers are in a particular sector of the plane, it is desirable to form the radiation in a beam directed towards that particular sector. On the other hand, when the receivers are generally distributed throughout the entire azimuth plane, and omnidirectional pattern is desired.

The form of the radiation pattern is generally determined by the geometrical and electrical properties of the antenna. In one particular case, an antenna with a particular helical geometry has been found admirably suited for omnidirectional propagation of electromagnetic radiation throughout the azimuth plane. Although such an antenna presents a radiation pattern that is substantially uniform throughout the azimuth plane, there is one narrow sector of the plane having an appreciable diminution of field strength. This sector may be termed the main null. The main null occurs because of the electromagnetic discontinuities at the coupling between the feed system and the antenna, introducing improper phase and amplitude distributions.

Heretofore, the main null has been cancelled by stacking a plurality of these antennas in a multi-bay system and by properly phasing each bay. However, it is more desirable to reserve the bay phasing to control the elevation pattern of the radiation. Further, the trend is toward the use of single bay systems because of the saving in apparatus and because of their smaller size. In single bay systems, there is no chance to cancel the main null by the proper phasing of the bays. In addition, these antennas have bandwidths of several percent of the operating frequency. Often this bandwidth is satisfactory but there are instances where broader beam bandwidths are desirable.

It is accordingly an object of the invention to provide an improved helical electromagnetic radiation system.

It is another object of the invention to provide an improved helical electromagnetic radiation system which transmits a modified radiation pattern which approaches a desired pattern.

It is a further object of the invention to provide an improved electromagnetic radiation system which includes an antenna having a particular helical geometry that minimizes the main null in the radiation pattern.

It is a still further object of the invention to provide means for increasing the beam bandwidth of a helical antenna.

Briefly, the invention is embodied in an electromagnetic radiation system which comprises a radiating transmission

line, having a helical configuration means for exciting the radiating transmission line and means for introducing a discontinuity at a point along the radiating transmission line to modify the pattern of radiation transmitted by the electromagnetic radiation system.

Other objects, features and advantages of the invention will be evident from the following detailed description when read with the accompanying drawings wherein:

FIGURE 1 is a diagrammatic representation of a portion of an electromagnetic radiation system, employing a helical radiative element, which is useful in describing the theory of the invention;

FIGURE 2 is a graph of field intensity (the abscissa) as a function of azimuth angle (the ordinate) of the radiation pattern of the electromagnetic radiation system of FIGURE 1;

FIGURE 3 is a diagrammatic representation of a portion of an electromagnetic radiation system employing a helical radiative element shown in perspective, in accordance with one embodiment of the invention;

FIGURE 4 is a sectional view of the system of FIGURE 3 taken along the line 4—4 of FIGURE 3;

FIGURE 5 is a diagrammatic representation of a portion of an electromagnetic radiation system, employing a helical radiative element shown in perspective, in accordance with another embodiment of the invention;

FIGURE 6 is a sectional view of the system of FIGURE 5 taken along the line 6—6 of FIGURE 5;

FIGURE 7 is a schematic representation of a portion of an electromagnetic radiation system employing a helical radiative element shown in perspective in accordance with a further embodiment of the invention;

FIGURE 8 is a sectional view of the system of FIGURE 7 taken along the line 8—8 of FIGURE 7; and

FIGURE 9 is a graph similar to the graph of FIGURE 2 to show the radiation pattern after the suppression of the main null.

Referring to FIGURE 1, a portion of an electromagnetic radiation system 10 is shown comprising a signal source 11 feeding an antenna 12. The antenna structure 12 is a diagrammatic representation of an electromagnetic radiation structure useful in describing the theory of the invention and may be of the type disclosed in British Patent No. 724,795 "Improvements in and Relating to Antenna Structures" of the assignee of the present application, which is to be regarded as prior art with respect to this present application. The signal source 11 generates a signal having a given carrier frequency or operating wavelength. The antenna 12 comprises a hollow cylinder 14 of an electrically conductive material, and first and second helices 16 and 18 of electrically conductive material developed about and spaced from hollow cylinder 14. Helix 16 starts from a point near a feed point or hole 22 in hollow cylinder 16 and progresses in a series of turns towards one end of hollow cylinder 14, and helix 18 starts from the same point and progresses in a series of turns towards the other end of hollow cylinder 14. Each turn of both helices 16 and 18 is an integral number of operating wavelengths in length. It should be noted that although one turn of each of the helices 16 and 18 is shown, these helices in general comprise a plurality of turns. Helix 16 and the portion of the surface of hollow cylinder 14 under helix 16 may be considered as a two-conductor transmission line. Similarly, helix 18 and the portion of the surface of hollow cylinder 14 under helix 18 may be considered as a two-conductor transmission line.

In particular, the helix 16 and the helix 18 are helical radiative conductors which extend in axially progressive turns about the hollow cylinder 14, which functions as a conductive support structure. The helix 18 is shown as a righthanded helix, that is, it is developed about the

hollow cylinder 14 from its starting point in the same manner as the threads of a righthanded screw. Similarly, the helix 16 is a lefthanded helix; that is, tracing it from its starting point, it follows a path similar to the path of threads of a lefthanded screw.

The helices 16 and 18 each has an axial helical length (aperture) preferably in the range between one and one-half and five operating wavelengths and a helix diameter and pitch such that the circumference of each turn preferably equals an integral number of operating wavelengths. The ends of each of the helices 16 and 18 may be supported free or in contact with the hollow cylinder 14.

By providing equicircumferential turns each of an integral number of operating wavelengths, all points on the helices 16 and 18 having the same azimuth direction radiate the same phase of signal. The electromagnetic radiation from these points interact with each other to provide an equiazimuth distributed radially propagated resultant electromagnetic wave which has a controlled elevation distribution.

There is a relationship between the radial spacing between a helix and the hollow cylinder and the length of the helix. There is a further relationship between these two dimensions and the helical pitch of the helices. In general, the radial spacing between a helix and hollow cylinder determines the characteristic impedance of the system. Also, the smaller the spacing between the hollow cylinder and a helix, the smaller the radiation per unit length of helix. Therefore, given a specific attenuation per unit length, it is possible to choose the length of the helix commensurate with radial spacing to insure that any signal propagated along a helix is substantially completely attenuated upon reaching the end remote from its energization terminal. Thus the termination of the helices is neither important nor critical.

A further understanding of these relations may be obtained by considering the helices and the central conductor to form sections of a radiating transmission line. Electromagnetic energization applied between adjacent ends of the helices and the hollow cylinder cause electromagnetic waves to travel along the length of the helices away from the points of energization. In order to constrain the propagation to travel in the helical path instead of the axial path as in a coaxial transmission line, the coupling between a turn of the helix and the hollow cylinder must be greater than the coupling between adjacent turns of the helix. In general, the helix pitch is greater than the radial spacing between the helix and the hollow cylinder. Furthermore, as the electromagnetic waves travel along the helices, they gradually decay due to the radiation of the electromagnetic energy from the helices. Therefore, by making the helices of sufficient length, reflections of electromagnetic waves from remote ends of the helices can be made substantially insignificant in effect. Typical values for a specific case would be 0.1 operating wavelengths radial spacing, 2 operating wavelengths per helical turn, .5 operating wavelengths helical pitch, 5 turns per helix, with 20-26 decibels of attenuation to the end.

To excite the transmission lines, a coaxial line 20 couples the signal source 11 to a feed point or hole 22 in hollow cylinder 14. In particular, the outer conductor of the coaxial line 20 is connected to the portion of the hollow cylinder 14 about the periphery of hole 22 and the central conductor of coaxial line 20 extends through hole 22 and is connected to helices 16 and 18. Upon excitation, electrical energy travels along the helices 16 and 18 and is progressively radiated.

A typical radiation pattern when each turn of the helices 16 and 18 is two operating wavelengths in length is shown in FIGURE 2. The curve 24 is a plot of relative field strength at different azimuth angles about the antenna 12 (FIG. 1). The azimuth angles are measured from the feed point or hole 22. Two types of nulls in the

radiation pattern are shown; cyclic nulls 26A to 26D and main null 28. The cyclic nulls 26A to 26D result from wavelength effects of the helices 16 and 18. There are two such nulls per operating wavelength of the turns. In general, these cyclic nulls 26A to 26D are in the order of one to two decibels and can be tolerated. The main null 28 is much more serious, it being in the order of eight to nine decibels.

The main null 28 is caused by higher order modes or harmonics of the excitation signal fed to the helices 16 and 18. These higher order modes are generated because there is not a smooth transition between the guided wave system of coaxial line 20 and the guided wave systems comprising helices 16 and 18 together with the hollow cylinder 14. In other words, there is an electromagnetic discontinuity at feed point or hole 22. This discontinuity causes the generation of high order modes which manifest themselves as a main null at a point in the range of between one-sixth and one-quarter of an operating wavelength from the feed point 22. The actual main null point may be found experimentally by measuring with conventional techniques the near field associated with the helices 16 and 18 and detecting a very significant and marked change in the near field. This very significant and marked change indicates the position of the main null.

It has been discovered that by introducing an impedance discontinuity, a cancelling discontinuity, at the main null point, it is possible to correct the proper phase and amplitude distribution and cancel the main null.

In general, a transmission line has a substantially constant impedance along its length. If there is an abrupt change in the impedance along the line, a discontinuity is introduced in the transmission line. The impedance discontinuity can be introduced by including a lumped impedance in the transmission line. This impedance is preferably a reactance.

Accordingly, FIGURES 3 and 4 show a lumped impedance introduced into the radiatable transmission lines of an electromagnetic radiation system 10A in accordance with one embodiment of the invention. Electromagnetic radiation system 10A is similar to electromagnetic system 10 of FIGURE 1 except for the introduction of the lumped impedances and reference characters with a postscript A will be employed for like elements and only the differences in the systems will be discussed in detail.

In particular, rings 30 and 32 are disposed about helix 18A and rings 34 and 36 are disposed about helix 16A. The rings 30 and 32 are positioned at a point along helix 18A in the range between one-sixth and one-quarter of an operating wavelength from the hole 22A. The exact point of positioning is determined by the location of the very great change in the near field associated with the helix 18A. The rings 34 and 36 are similarly positioned on helix 16A. The rings 30, 32, 34 and 36 may be either of an electrically conductive material or a material having a high dielectric constant and low loss tangent. By low loss tangent is meant the imaginary part of the dielectric constant is very small and it absorbs very little radio frequency energy if it is placed in the R.F. transmission system. In a particular embodiment it has been found that rings having a diameter of one thirty-second of an operating wavelength performed admirably.

FIGURES 5 and 6 show an electromagnetic radiating system 10B in accordance with another embodiment of the invention wherein the lumped impedances are inserted in the inner conductor of the transmission line. Electromagnetic radiation system 10B is similar to electromagnetic radiation system 10 of FIGURE 1 except for the introduced lumped impedances and reference characters with a postscript B will be employed for like elements and only the differences will be discussed in detail.

More particularly, bosses in the form of screws 40 and 42 are fixed in hollow cylinder 14B under helix 18B,

and bosses in the form of screws 44 and 46 are fixed in hollow cylinder 14B under helix 16B. It should be noted that screws have the added advantage of permitting fine adjustments of the lumped impedances. The screws 40 and 42 are located under helix 18B at a point where there is a very great change in the near field associated with the helix 18B. This change will be somewhere between one-sixth and one-quarter of an operating wavelength from hole 22B. The screws 44 and 46 are similarly located in hollow cylinder 14B under helix 16B.

A further embodiment of the invention is shown in the electromagnetic radiation system 10C of FIGURES 7 and 8. Electromagnetic radiation system 10C is similar to electromagnetic radiation system 10 of FIGURE 1 except for the introduced lumped impedances and reference characters with a postscript C will be used to designate like elements and only the differences will be discussed in detail.

More particularly, a parasitic element 50 is interposed in the space between helix 18C and hollow cylinder 14C, and a similar parasitic element 52 is interposed in the space between helix 16C and hollow cylinder 14C. The parasitic element 50 is located between one-sixth and one-quarter of an operating wavelength from the hole 22C along the length of helix 18C. The exact position is determined by the above-mentioned near field measurements. Parasitic element 52 is similarly positioned.

The parasitic element 50 is a length of electrical conductor 54 supported on dielectric standoff 56 (FIG. 8). Electrical conductor 54 is disposed parallel to helix 18C. It should be noted that near field measurements will be required to determine the length of electrical conductor 54. That is, the length of electrical conductor 54 is correct when the near field phase and amplitude distribution measurements are proper.

It should be noted that by employing the various embodiments of the invention, it is possible to not only suppress the main null by 4.5 to 6.5 decibels but also to increase the beam bandwidth to greater than ten percent. FIGURE 9 shows such an improvement in the radiation pattern.

There has thus been disclosed improved electromagnetic radiation systems which transmit modified radiation patterns that approach a desired radiation pattern. In particular, the electromagnetic radiation systems, according to several embodiments of the invention, transmit radiation patterns in an azimuth plane that are omnidirectional with substantially constant field strength in all azimuth directions because the main null has been suppressed. There has further been disclosed, in electromagnetic radiation systems which include antennas having a particular helical geometry, means for minimizing the main null in the radiation pattern. In fact, by employing the embodiments of the disclosed lumped impedances it is possible to cause a diminution of the main null by up to eight decibels.

While only several representative embodiments of the invention have been disclosed in detail, there will be obvious to those skilled in the art many modifications and variations accomplishing the foregoing objects and realizing many or all of the advantages but which do not depart essentially from the spirit of the invention.

What is claimed is:

- An electromagnetic radiation system comprising a first electrical conductor, said first conductor being substantially linear, a second electrical conductor developed about said first electrical conductor in a helical configuration, said first and second electrical conductors cooperating to provide a radiating transmission line, a source of signal of given operating wavelength for exciting said radiating transmission line, coupling means for coupling said source of signal to said radiating transmission line, and loading means for introducing a cancelling discontinuity positioned in a region along the length of said radiating transmission line to minimize the main azimuth null in the radiation pattern caused by the electromagnetic discontinuity introduced by said coupling means.

- The electromagnetic radiation system of claim 1 wherein said means for introducing the cancelling discontinuity is a ring of electrically conductive material developed about said second electrical conductor.

- The electromagnetic radiation system of claim 1 wherein said means for introducing the cancelling discontinuity is a ring material of high dielectric constant developed about said second electrical conductor.

- The electromagnetic radiation system of claim 1 wherein said means for introducing the cancelling discontinuity is a screw fitted in said first electrical conductor.

- The electromagnetic radiation system of claim 1 wherein said means for introducing the cancelling discontinuity is a parasitic element disposed between said first and second electrical conductors.

- The electromagnetic radiation system of claim 1 wherein the region of introduction of said cancelling discontinuity along said radiatable transmission line is where there is a very large change in the near field.

- The radiation system of claim 1 wherein the region of introduction of said cancelling discontinuity along said radiatable transmission line is between one-sixth and one-quarter of an operating wavelength from said coupling means.

- An electromagnetic radiation system comprising a first electrical conductor, said first electrical conductor being substantially linear, a second electrical conductor developed about said first electrical conductor and extending toward a first end of said first electrical conductor, a third electrical conductor developed about said first electrical conductor and extending toward the second end of said first electrical conductor in a helical configuration, said first, second and third electrical conductors cooperating to provide a radiatable transmission line system, a source of signal of given operating wavelength for exciting said radiatable transmission line system, coupling means for coupling said source of signal to said radiatable transmission line system, and loading means for introducing cancelling discontinuities positioned in regions along said radiatable transmission line system to minimize the main azimuth null in the radiation pattern caused by the electromagnetic discontinuity introduced by said coupling means.

- The electromagnetic radiation system of claim 8 wherein said means for introducing cancelling discontinuities are rings of electrically conductive material developed about said second and third electrical conductors.

- The electromagnetic radiation system of claim 8 wherein said means for introducing cancelling discontinuities are rings of high dielectric constant material developed about said second and third electrical conductors.

- The electromagnetic radiation system of claim 8 wherein said means for introducing cancelling discontinuities are screws fitted in said first electrical conductor.

- The electromagnetic radiation system of claim 8 wherein said means for introducing cancelling discontinuities are parasitic elements interposed between said first and second electrical conductors and between said first and third electrical conductors.

- The electromagnetic radiation system of claim 8 wherein the regions of introduction of said cancelling discontinuity along said transmission line system is where there is a great change in the near field.

- The electromagnetic radiation system of claim 8 wherein the regions of introduction of said cancelling discontinuities along said radiatable transmission line system are from between one-sixth and one-quarter of an operating wavelength from said coupling means.

- An electromagnetic radiation system comprising a cylindrical conductor, a first radiative conductor, said

first radiative conductor being a righthanded helix of given pitch developed about said cylindrical conductor toward a first end of said cylindrical conductor, a second radiative conductor, said second radiative conductor being a lefthanded helix of the same given pitch developed about 5 said cylindrical conductor toward the other end, each of the turns of each of the helices of said radiative conductors having the same integral number of operating wavelengths, said cylindrical conductor and said first and second radiative conductors cooperatively disposed to 10 provide a radiatable transmission line system, signal feeding means coupled to said first and second radiative conductors to feed signal energy to said first and second radiative conductors, and means for introducing cancelling discontinuities at regions along said radiatable transmission line system to minimize the main null in the radiation 15

pattern caused by the electromagnetic discontinuity introduced by said coupling means.
